UNITED STATES PATENT OFFICE.

HIRAM W. WILSON, OF COYLE, OKLAHOMA.

GATE.

Application filed April 28, 1927. Serial No. 187,187.

This invention relates to new and useful improvements in gates, doors, and similar closures and has for its primary object to provide a device of this character adapted 5 to be operated by a vehicle approaching the gate to cause the automatic opening thereof, the mechanism being so constructed that when the vehicle has passed through the gate the same will automatically return to closed 10 position.

An important object of the invention is to substantially improve and simplify over 15 gates of this general character heretofore patented.

With the foregoing and other objects in view as the nature of the invention will be better understood, the same comprises the 20 novel form, combination and arrangement of parts hereinafter more fully described shown in the accompanying drawing and claimed.

In the drawing wherein like reference characters indicate corresponding parts in both of the views:

Figure 1 is a transverse section of a roadway equipped with a gate constructed in accordance with the present invention, the mechanism being disclosed in full line closed 25 position and in dotted line partially open 30 position, and

Figure 2 is a longitudinal section through the road equipped with the improved gate.

Now having particular reference to the drawing 5 indicates the road surface, transversely beneath which the earth is formed with a narrow pit 6. The road surface is removed from above the pit and at a predetermined area at opposite sides thereof and disposed within the opening in the road for closing the top of the pit is a bridge panel 7. The opposite ends of this panel 7 are supported by concrete walls 8—8 arranged perpendicularly within the opposite ends of the pit 6 as clearly disclosed in Fig. 1.

Arranged upon opposite ends of the bridge plate 7 are spaced vertical brackets 9—9 between the upper ends of each pair of which are pivotally arranged the lower ends of gate actuating levers 10—10, these levers 45 extend inwardly and upwardly as indicated in Figure 1 and have arranged therebetween a gate unit A, which unit is pivoted to the ends of the levers 10—10 as at 11. Pivotally secured to these levers 10—10 of each 50 gate unit are the upper ends of downwardly extending link bars 12—12 that are movable

in each instance through an opening 13 at the adjacent end of the bridge plate 7. To the lower ends of these bars are pivotally secured elongated bars 14—14 that extend inwardly and upwardly within the pit 6, the bars of the opposite gate units crossing at the center of the bridge plate 7 and being pivoted as at 15 to depending hangers 16—16 bolted upon the under side of the bridge 60 plate 7 at the direct center thereof.

The extreme inner ends of all the bars 14 have pivotal connection with upwardly extending links 17 that are freely movable through openings 18 in the bridge plate 7, 70 while the upper ends of those links at opposite sides of the longitudinal center of the bridge plate 7 are pivoted to the adjacent edge of a vehicle operated platform 19. As disclosed in both of the figures, these ends 75 of the platforms are elevated, while the opposite ends thereof rest upon the surface of the road 5. Obviously as a vehicle approaches the gate mechanism from either side, that particular platform 19 is forced 80 downwardly by the weight of the vehicle for so moving the links 17, bars 14, and 12 as well as the gate attached levers 10 to swing the same upwardly in the direction of the arrows in Figure 1 and as suggested by the 85 partially open position of the gates indicated by the dotted lines in the same figure. After the vehicle passes over the platform at the opposite side of the gate structure the weight of the gates will cause the same to drop 90 downwardly into closed position for preventing the passage of animals therethrough.

In a view of the foregoing description when considered in conjunction with the accompanying drawing it will be apparent 95 that I have provided a highly novel, simple, and efficiently operating gate structure that is well adapted for all purposes heretofore designated, even though I have herein shown and described the invention as consisting of 100 certain detail structural elements it is nevertheless to be understood that some changes may be made therein without affecting the spirit and scope of the appended claim.

Having thus described the invention, what 105 I claim as new is:

In a road gate of the character described wherein the road is formed with a transversely extending pit, a transverse panel arranged upon the top of the pit for affording 110 a closure therefor, upwardly and normally inwardly extending levers pivoted to the

panel adjacent opposite ends thereof, gate units pivoted horizontally to the outer ends of the levers, bars pivoted at their upper ends to the said levers and depending into the pit through openings in the panel, inwardly and upwardly extending bars pivoted at their lower ends to the lower end of said first mentioned bars, pivotal connections between the bars and the interior of the pit, weight operated platforms disposed

along the road surface at opposite sides of the gate, and means connecting the inner ends of the platforms and the ends of said last mentioned bars so that when pressure is applied thereto, said bars will be so operated as to cause the movement of the gate attached levers to cause the raising of said gate units. 15

In testimony whereof I affix my signature.

HIRAM W. WILSON.
